UNITED STATES PATENT OFFICE

150,110

DESIGN FOR A FISH LURE

Josephine M. Cole, Detroit, Mich.

Application April 11, 1946, Serial No. 128,476

Term of patent 14 years

(Cl. D31—4)

To all whom it may concern:

Be it known that I, Josephine M. Cole, a citizen of the United States, residing at Detroit, county of Wayne, in the State of Michigan, have invented a new, original, and ornamental Design for a Fish Lure, of which the following is a specification, reference being made to the accompanying drawing, forming part thereof.

Fig. 1 is a top plan view of a fish lure embodying my new design.

Fig. 2 is a side elevation thereof.

Fig. 3 is a front elevation thereof.

I claim:

The ornamental design for a fish lure, as shown.
JOSEPHINE M. COLE.
